DESIGN FOR A HAT

Samuel Schaffer, Bronx, N. Y.

Application May 2, 1934, Serial No. 51,666

Term of patent 3½ years

To all whom it may concern:

Be it known that I, SAMUEL SCHAFFER, a citizen of the United States, residing in the Bronx, in the county of the Bronx and State of New York, have invented a new, original, and ornamental Design for a Hat, of which the following is a specification, reference being had to the accompanying drawing, forming part thereof.

The dominant feature of the present design is the ornamental effect produced by the skull cap having a rim provided with a serrated upper edge portion.

I claim:

The ornamental design for a hat, as shown and described.

SAMUEL SCHAFFER.
